Filed Nov. 5, 1973, Ser. No. 412,591

Term of patent 7 years

Int. Cl. D10—04

U.S. Cl. D10—46

FIG. 1 is a front, side and top perspective view of the depth finder or similar article showing my new design;

FIG. 2 is a front elevational view thereof;

FIG. 3 is a left side elevational view thereof, with the transducer arm for said article shown in an alternate folded position extending at 90° relative to the position of the transducer arm as illustrated in FIG. 1, and shown with a broken portion at the end of the transducer arm in such alternate position;

FIG. 4 is a rear elevational view thereof; and

FIG. 5 is a bottom plan view thereof.

I claim:

The ornamental design for a depth finder or similar article, as shown and described.
